COMBINED GRAVE MARKER AND
FLOWER VASE

Frank V. Ross, Indianapolis, Ind.

Application July 3, 1950, Serial No. 171,932

3 Claims. (Cl. 47—41)

1

This invention relates to a combined grave marker and flower vase. In those grave markers in use today with which a flower vase is combined, it is generally necessary to remove the vase, turn it upside down to release the water which has accumulated therein and then remount the vase within the marker prior to placing flowers therein. Substantially the same procedure must be followed when it is desired to dispose of the flowers and return the vase to its non-use position.

It is the primary object of this invention to provide a grave marker having a flower vase carried by and movable with a hinged closure plate in such manner that water will readily drain from the vase when it is not in use, and so that it may easily be pivoted to its upright, flower supporting position.

It is a further object of this invention to provide a grave marker having a flower receptacle which carries a supplementary closure plate which will cover the otherwise exposed opening of the receptacle well when the receptacle is disposed in its upright, flower-supporting position.

The primary feature of the present invention resides in the provision of a closure plate for the well in which the receptacle is disposed, said plate carrying and moving with it the receptacle itself. When the receptacle is in its concealed position, the closure plate to which it is secured is operable to close the well. When the receptacle is in its upright, flower-supporting position, the supplementary closure plate carried by the receptacle is operable to close that opening of the well between the receptacle and the side wall of the well.

A further feature of the present invention resides in the provision of a drain through one side of the well. Once the flowers in the receptacle have wilted or otherwise served their purpose, they may be removed and the receptacle then pivoted to concealed position either by the foot or by the hand, whereupon the water therein will automatically be spilled out into the bottom of the well, and from thence drained out into the surrounding ground.

A still further feature of the present invention resides in the particular manner in which the receptacle-receiving well is supported, and in the construction and arrangement of the marker anchoring means.

The full nature of the invention will be understood from the accompanying drawings and the following description and claims:

2

In the drawings Fig. 1 is a top plan view of the invention.

Fig. 2 is a section view taken on line 2—2 of Fig. 1 in the direction of the arrows.

Fig. 3 is a section view taken on line 3—3 of Fig. 2 in the direction of the arrows.

In the drawings, Fig. 1 shows generally the grave marker comprising a bronze or the like plate 10 exposed to view and substantially level with the top of the ground 11. On the marker there is formed the usual legending 12 giving the name of the decedent together with the date of his birth and death. In order to make possible the locating and anchoring of the marker, it is first necessary that a hole be dug in the burial tract to approximately the depth, width and length of an iron box-like structure 13. After the box is positioned within the hole and the earth tamped down therearound, concrete is poured in it preferably up to a point slightly below the bottom of the well 14 in which the receptacle is housed. Next, a metal plate or strap 15 is bolted or otherwise suitably secured at 16 to the inner end walls of the box slightly below the top edges thereof. This strap extends longitudinally of the marker and has a substantially U-shaped central portion which defines generally the width of the well. Formed in the strap are at least two apertures 17 for purposes hereinafter explained.

Secured by rivets 18 or other suitable means to the inner face of the U-shaped portion of the strap is the copper well-defining box 19. It will be observed that the upper extremities of this box are outwardly flanged and bear upon the bottom of the marker. Formed through one wall of box 19 and through the adjacent wall of box 13 are the aligned openings 20 through which is extended the drain spout 21 to permit water to drain from the bottom of the well to the surrounding earth.

Once the strap 15 has been secured in position along with the copper box 19, additional concrete is poured into box 13 until it is substantially level with the top thereof. Thereupon anchoring members 22 are extended downwardly into the concrete through bosses 23 depending from the marker, and through apertures 17 formed in the strap 15. These anchoring members are preferably but not necessarily provided with annular ribs 24 to anchor the marker more securely in fixed position.

The flower receiving receptacle consists of the side and bottom walls 25. It is hingedly connected at either side by screws 26 to the bosses

27 depending from the marker 11. In order to provide additional hinged support, the inner face of the receptacle has formed therein the bosses 28 which have apertures in alignment and register with apertures formed in the bosses 27 so that the screw may be threadedly accommodated therein.

It will be observed that the marker 10 has a centrally disposed opening 29 formed therein. A closure plate 30 therefor is secured to the wall of the receptacle that is exposed when it is in its horizontal, concealed position. This closure plate is so positioned and is of such length and width that it, together with the confronting wall of the receptacle, effectively seals off the interior of the well when in closed position (see Fig. 3).

Projecting outwardly from the wall of the receptacle opposite to the closure plate is a supplementary closure member 31 which is formed to a length and width such that it spans the opening between the receptacle and the marginal edge of the marker that defines opening 29, when the receptacle is in its vertical position. This member has a spring metal strip 32 secured thereto at 33, the extremities of which have a return loop formation. A portion 34 of each loop projects outwardly from the side edges of closure 31 and serves as catch means. A pair of substantially U-shaped latch elements 35 depend from the marker adjacent the marginal edges that define opening 29 and at one end thereof, these elements being so positioned that when the receptacle is pivoted to its upright position, the projecting loop portions 34 are in frictional contact therewith. By reason of this construction, once the receptacle has been pivoted to its vertical flower receiving position, the supplementary closure member 31 not only spans the exposed opening between the vase and the marker but also retains the receptacle in its upright position so that it will not pivot downwardly until such a time as sufficient pressure is applied thereto to overcome the frictional connection between the loop portions and the substantially U-shaped members 35.

It will be observed that a bevelled detent or notch 36 is formed in the marginal edge of the marker adjacent the free end of the closure plate 30 so that when it is desired to pivot the receptacle to its upright position it will be possible to grasp the edge of the closure plate with a finger of the hand.

The operation of the invention is believed to be apparent from the foregoing description. However, when the receptacle is not in use it will be disposed in a horizontal, concealed position (see Fig. 3), at which time the well accommodating the receptacle, and the marker opening, will be closed by the closure plate 30. When it is desired to expose the receptacle by pivoting it to its upright position shown in dotted lines in Fig. 3, it is necessary only to place a finger or thumb into the notched portion 36 until the edge of the closure plate can be grasped whereupon it is pivoted upwardly. At such time the supplementary closure member 31 will be in frictional and resilient engagement with the U-shaped element 35, thereby retaining the receptacle in its upright position, and in addition closing off the exposed opening in the marker and the well. When the flowers placed in the receptacle have wilted or otherwise have served their purpose, the receptacle may be moved with the hand, kicked with the foot or thrust in any other way in a downward direction, the impact

being such that the resilient connection between the loop portions 34 and the U-shaped elements will be overcome. The sudden downward movement of the receptacle will automatically, by reason of centrifugal force, spill out any water remaining therein, into the bottom of the well from whence it will be drained into the surrounding ground through the drain 21. In order to facilitate release of the water from the receptacle when it is pivoted downwardly the upper ends have a radius 37 formed therein.

While the invention has been illustrated and described in great detail in the drawings and foregoing description, the same is to be considered as illustrative and not restrictive in character.

The invention claimed is:

1. A combined grave marker and flower receptacle, comprising a marker having an opening, a pivoted closure for said opening, said closure including a flower receptacle formed on the under surface thereof, said receptacle being movable therewith from a concealed position to an upright, flower receiving position, a well structure for receiving said receptacle formed immediately below said closure and being of a size substantially greater than the size of said receptacle, a second closure integral with said receptacle and disposed on the opposite side thereof from said first closure, said second closure having an area substantially equal to the space in said marker opening that remains exposed when said receptacle is in upright position.

2. A combined grave marker and flower receptacle comprising a marker having an opening formed therethrough, a closure for said opening, said closure carrying a flower receiving receptacle on the under surface thereof, said receptacle being movable therewith from lowered to raised position, means pivotally connecting said receptacle to said marker, a well structure disposed below said marker within which said receptacle is receivable, and a second closure secured to said receptacle and projecting outwardly from the side thereof opposite said first closure and at substantially right angles to said first closure, said second closure being formed to a size substantially equal to the space in said marker opening that remains exposed when said receptacle is in upright position, latch means carried by said marker adjacent its opening, and catch means connected to said second closure and being releasably engageable with said latch means upon said receptacle being raised to upright position.

3. A combined grave marker and flower receptacle comprising a box-like structure adapted to be embedded within the ground and having an open top, said structure being adapted to receive concrete or the like therewithin, a well defining box disposed within said structure, means connected to said structure and supporting said box, a marker covering the top of said structure and having an opening formed therethrough immediately above and in communication with said well, a closure plate for said opening having a hinged connection with said marker, said closure plate carrying a flower receiving receptacle on the under surface thereof, said receptacle being received and accommodated within said well, an outlet in communication with said well and the surrounding ground, and a second closure plate projecting from the side of said receptacle opposite to said first closure plate and being of a size sufficient to close the space in said marker

opening that is exposed when said closure plate and receptacle are pivoted to raised flower receiving position, latch means carried by said marker adjacent its opening, and catch means connected to said second closure and being releasably engageable with said latch means upon said receptacle being raised to upright position.
